Inventor

United States Patent Office.

JOSEPH R. SMITH, OF CHICAGO, ILLINOIS.

Letters Patent No. 94,357, dated August 31, 1869.

IMPROVED MOTH-PROOF LINING.

The Schedule referred to in these Letters Patent and making part of the same.

To all whom it may concern:

Be it known that I, JOSEPH R. SMITH, of the city of Chicago, in the county of Cook, and State of Illinois, have invented certain new and useful Improvements in "Moth-Proof Lining;" and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

The object of my invention consists in rendering the receptacles for cloth, furs, and other articles of wearing-apparel or goods, moth-proof, by lining the said receptacles on the inside with red-cedar wood, camphor-wood, or other wood suitable for the purpose, in the manner as will be hereinafter fully explained.

I take thin veneers of red-cedar wood, or camphor-wood, and I paste, glue, or otherwise affix them on cloth or paper, in such a manner as to make a kind of cloth, with which cloth I line, on the inside, boxes, trunks, drawers of bureaus, or any other receptacle or receptacles in which the wearing-apparel, or any other articles of goods, are to be placed and kept for the

purpose of saving the same from the ravages of the moth.

The red-cedar wood, camphor-wood, and some other species of wood, being highly aromatic, prevent the breeding of the moth in articles surrounded on all sides by the same; and, in using my moth-proof lining, it shall always be affixed to the inner walls of various receptacles, with the cedar or camphor-wood veneering out, and the cloth or paper next to the said walls.

Although I am aware that solid red-cedar and camphor-wood boxes have been used for the same object as mine, yet, I claim, with my moth-proof lining, the same object can be attained far more cheaply, and more economically.

Having thus fully described my invention, What I claim as new, and desire to secure by Letters Patent, is—

A new article of manufacture, made by uniting a veneer of red-cedar, camphor, or similar wood, with paper or cloth, as herein described, for the purpose of lining boxes, trunks, drawers, &c., as set forth.

JOSEPH R. SMITH.
